UNITED STATES PATENT OFFICE.

GUSTAVE S. CARLSON, OF ST. PAUL, MINNESOTA.

DESIGN FOR A GOBLET OR SIMILAR ARTICLE.

Application filed January 28, 1924. Serial No. 8,465. Term of patent 3½ years.

To all whom it may concern:

Be it known that I, GUSTAVE S. CARLSON, a citizen of the United States, residing at St. Paul, in the county of Ramsey and State of Minnesota, have invented a new, original, and ornamental Design for Goblet or Similar Article, of which the following is a specification, reference being had to the accompanying drawing, forming part thereof.

The figure is a plan view of a glass goblet, showing my new design.

I claim:

The ornamental design for a goblet or similar article, as shown.

GUSTAVE S. CARLSON.
